WAVE PRESSER

Nathan L. Solomon, Brooklyn, N. Y.

Application July 26, 1934, Serial No. 736,981

12 Claims. (Cl. 132—31)

The subject matter of this invention is a wave presser particularly adapted to removably embrace or straddle a wave of hair for processing thereof without injury to the scalp. Broadly speaking the invention is especially concerned with cooperating arcuate complementary clamping jaws constituting means for initially collecting a wave having a wide crest of relatively small height between the gap of the jaws and subsequently modulating the wave to accentuate the latter by increasing the height thereof during movement of the jaws towards each other whereby the modulated wave has its longitudinally disposed sides retained in vertical juxtaposition and held in contact by relatively elongated opposing rectilinear portions of the clamping or pressing jaws.

The primary object of the invention resides in the provision of a conveniently manipulatable wave presser having a relatively wide housing for receiving the bottom or thickest part of the wave and comprising relatively flat intermediate opposing clamping portions for progressively increasing the slope of upper part of the wave and firmly compress the sides of the latter between the intermediate clamping portions of the wave presser.

The invention has as another object to provide reinforced hingedly associated longitudinally curved hair pressing complements having depending and opposing curved bead portions each including laterally and inwardly extending teeth adapted to intermesh and be disposed substantially in the same plane, the cooperating teeth serving to collect a wave to be processed between the complements and pursuant to the closing of the latter cooperating to form a seat to permit the wave presser to comfortably rest on or adjacent the scalp.

Other objects, advantages and features of the invention are in part obvious and in part pointed out hereinafter, however, the novel features characterizing the invention are set forth in the appended claims although it is to be understood, that the invention both as to its organization and the method of operation, together with the objects, features and advantages thereof will be best understood from the following description of several specific embodiments when read in connection with the accompanying drawing in which:

Fig. 1 is an end view of the wave presser according to the invention, shown open, and grasping a relatively flat wave of hair.

Fig. 2 is a view similar to Fig. 1 but illustrating the complementary jaws of the wave presser mov-

ing towards each other and increasing the height of the wave grasped between the jaws.

Fig. 3 shows another end view of the wave presser jaws about to close.

Fig. 4 is an end view of the complementary jaws shown closed and grasping the attenuated part of the wave.

Fig. 5 is a perspective view of a wave after having been modulated or processed.

Fig. 6 is a bottom view of the hair presser illustrated in Figs. 1-4 inclusive, showing the laterally disposed teeth of opposing complementary clamping portions disposed in the same plane.

Fig. 7 is a front elevational view of another form of wave presser and

Fig. 8 is a section on the line 8—8 of Fig. 7.

Referring to the drawing, the hair wave presser is generally designated 10 and comprises a pair of longitudinally curved hingedly connected complementary clamping or pressing members 11 and 12. Each of these members constitutes a clamping jaw having an elongated rectilinear pressing perforated intermediate portion 13 from which integrally depends a hollow bead broadly denoted 14. Each bead is coextensive the length of a respective intermediate portion 13 and includes a laterally extending flange 15 which is perpendicular to its intermediate portion 13, a downwardly and outwardly intermediate curved part 16 integrally merging with a cooperating downwardly and inwardly curved part 17 having a plurality of spaced tapering teeth 18, the teeth of the companion members being disposed transversely of a respective rectilinear portion 13 and embodying relatively flat faces 19 adapted to seat on the scalp. The teeth of the companion members, intermesh and are disposed in the same plane being perpendicular to the intermediate portions 13. The teeth 19 are arranged to extend the entire length of the companion beads which form a relatively wide housing or longitudinally curved channel for the reception of the thickest portion or base of a wave to be treated after the latter has been collected by the cooperative teeth of the companion jaws.

In the form according to Figs. 1 to 4 inclusive the complementary jaws are provided with an arcuately disposed strengthening or reinforcing rib 20 at corresponding upper portions thereof.

Extending upwardly and outwardly from the upper portion of each of the jaws is a centrally arranged rectilinear manipulator 21 each of which includes an inwardly projecting transversely disposed perforated ear 22, the adjacent ears of the manipulators being pivotally sus-

tained on a stationary fulcrum rod 23 about which is encircled longitudinally thereof a helicoidal spring 24 having one free terminal as 25 normally abutting an inner inclined face of one of the 5 manipulators 21 and a similar free terminal at the other end thereof abutting an opposing inclined face of the opposing manipulator of the companion jaw as is well understood for normally urging the cooperating manipulators outwardly 10 and consequently hold the intermediate rectilinear portions in close vertical proximity such that the relatively wide and flat teeth of the depending beads of the complementary jaws will be normally in mesh.

15 To facilitate drying of the wave after having been clamped between the jaws, each of the rectilinear portions 13 thereof is provided with a plurality of perforations 24.

In Fig. 1 the complementary members are 20 spread apart and the teeth thereof are engaging the hair of a relatively flat wave at the base thereof. To open the jaws, the operator moves the manipulators 21 towards each other. By gradually releasing pressure from these manipulators the toothed beads move towards each other 25 automatically by reason of the action of helicoidal spring 24.

In moving towards each other the teeth collect the hair at the base of the wave, causing 30 the intermediate or attenuated part thereof to rise (see Fig. 2), such that the more pronounced crest is disposed between the upper parts of the intermediate rectilinear portions 13, and just prior to the closing of the jaws, the sides of the 35 wave are disposed substantially in vertical juxtaposition (see Fig. 3) after which the complementary members of the jaws close, pressing the sides of the wave together between the elongated straight portions 13, the base of the wave, however, is disposed within the toothed companion 40 beads, with the teeth thereof supported within close proximity of or resting on the scalp without injuring the latter.

With the pressing of the wave accomplished, 45 the jaws may be conveniently disconnected therefrom, by pressing the manipulators towards each other and subsequently bodily removing the wave presser from the head. The wave pressed takes the form shown in Fig. 5.

50 In the form according to Figs. 7 and 8, the rectilinear intermediate portions 13 of companion jaws are each provided with a longitudinally disposed arcuately arranged strengthening rib 20 disposed centrally thereof. In the form 55 shown in Figs. 1 to 4 inclusive, a similar reinforcing rib 20 is disposed at an upper remote portion of a respective jaw. In Figs. 1 to 8 inclusive the manipulators each includes a reinforcing rib 26 and perforations as 27. In other aspects, the modification illustrated in Figs. 7 to 8 is identical with the embodiment disclosed in connection with Figs. 1 to 4 inclusive.

While reference in the specification and claims is made to the expressions "in mesh" or "intermeshed" it is conceivable that other equivalent expressions may be used, for example, if manual pressure be removed from the reinforced manipulatable portions 21 after the beads of the companion jaws have been spread apart, the jaws close and the teeth of the beads thereof are disposed in a unitary plane and accordingly the teeth of these beads may be considered as "intermeshed", "in mesh" or "interlocked", however, it is recognized that the invention need not be limited to these expressions or terms and con-

sequently strict interpretation thereof is therefore not contemplated.

The herein disclosed and described embodiments have given satisfactory results and it will be obvious to those skilled in the art, after an understanding of my invention, that other changes and modifications may be made without departing from the spirit and scope of the invention and it is intended that all matter contained in the above description or shown in the accompanying drawing shall be interpreted as illustrative and not in a limiting sense. 10

I claim:—

1. A hair wave presser, comprising, in combination, juxtaposed hingedly connected complementary clamping jaws each having a relatively elongated intermediate rectilinear portion, a hollow bead integrally depending from each intermediate portion of said jaws, each bead having a lower free portion comprising inwardly disposed spatially arranged teeth, and means normally holding the rectilinear portions of said jaws in close proximity and the teeth of said beads intermeshed, said beads constituting a housing for receiving and grasping the base of a wave of hair straddled by said jaws. 15

2. A hair wave presser, comprising, in combination, juxtaposed hingedly connected complementary longitudinally curved clamping jaws each having a relatively elongated intermediate rectilinear portion, a hollow bead integrally depending from each intermediate portion of said jaws and coextensive the length thereof, each bead having a lower free portion disposed transversely relative to a respective jaw and comprising spatially arranged terminal teeth, and means normally holding the rectilinear portions of said jaws in close proximity and the teeth of said beads intermeshed and disposed in a unitary plane. 20

3. A hair wave presser, comprising, in combination, juxtaposed hingedly connected complementary longitudinally curved clamping jaws each having intermediate rectilinear portions comprising a depending and outwardly projecting hollow bead coextensive the length thereof, said beads comprising facing longitudinally and inwardly disposed channels for receiving a relatively thick portion of a wave interposed between said jaws, said beads having free terminal teeth projecting inwardly and adapted to intermesh and normally disposed in a unitary plane in the closed position of said jaws, and means for normally holding said jaws closed. 35

4. A hair wave presser, comprising, in combination, juxtaposed hingedly connected complementary longitudinally curved clamping jaws each having a longitudinally curved outwardly projecting hollow bead comprising inwardly disposed terminal teeth, the teeth of said beads normally intermeshing and disposed in a unitary arcuate plane, and means cooperating with said jaws for normally holding said teeth in mesh. 40

5. A hair wave presser, comprising, in combination, juxtaposed hingedly connected complementary longitudinally curved clamping jaws each having a longitudinally curved outwardly extending depending hollow bead defining a housing for receiving a relatively wide portion of a wave interposed between said jaws, each of said beads having free inwardly disposed teeth, the teeth of said beads intermeshing in a unitary arcuate plane and constituting an arcuate seat and means for normally holding said jaws closed and said teeth in mesh. 55

6. A hair wave presser, comprising, in combination, juxtaposed hingedly connected comple- 60

mentary clamping jaws each having a free depending hollow bead comprising inwardly extending free teeth, the teeth of said beads being normally in mesh and disposed in the same plane, 5 and means for normally holding said jaws closed and the teeth of said beads intermeshed.

7. A hair wave presser, comprising, in combination, juxtaposed hingedly connected complementary clamping jaws each having a free depending hollow bead each presenting an inwardly disposed channel, the channels of said beads constituting a housing for removably receiving a relatively wide portion of a wave interposed between said jaws, each of said beads having terminal and inwardly disposed spaced free teeth, the teeth of said beads being normally in mesh and disposed in a unitary plane, and spring means 10 cooperating with said jaws for normally holding the latter closed and the teeth of said beads 15 intermeshed.

8. A hair wave presser, comprising in combination, juxtaposed hingedly connected complementary clamping jaws each having an intermediate rectilinear perforated portion, a free depending hollow bead integrally connected to each portion, each bead of said jaws having inwardly disposed free teeth, the teeth of said beads being normally in mesh and disposed in the same plane, and spring means 20 cooperating with said jaws for normally holding the latter closed and the teeth of said beads 25 intermeshed.

9. A hair wave presser, comprising, in combination, juxtaposed hingedly connected complementary clamping jaws each having an intermediate rectilinear perforated portion each comprising a reinforcing rib extending longitudinally thereof, an outwardly projecting depending hollow bead integrally connected to each portion, each bead having inwardly disposed free spaced 30 teeth, the teeth of said beads being normally in mesh and arranged in the same plane, and means cooperating with said jaws for normally holding said rectilinear portions in close proximity and said teeth intermeshed.

45 10. A hair wave presser, comprising, in combination, juxtaposed hingedly connected longitudi-

nally curved complementary clamping jaws each having an intermediate rectilinear perforated portion coextensive the length thereof, each portion comprising a longitudinally disposed reinforcing rib, an outwardly projecting hollow bead integrally connected to each of said portions, each bead of said jaws having inwardly disposed terminal free spaced teeth, the teeth of said beads being normally in mesh and disposed in a unitary longitudinal arcuate plane, and spring means 10 for normally holding said jaws closed and the teeth of said beads intermeshed.

11. A hair wave presser, comprising, in combination, juxtaposed hingedly connected longitudinally curved complementary clamping jaws 15 each having an intermediate reinforced and perforated rectilinear portion coextensive the length thereof, each bead comprising a laterally disposed flange integral with a respective rectilinear portion, an outwardly and downwardly curved portion merging with said flange, a downwardly and inwardly curved part merging with said outwardly and downwardly curved portion, and inwardly disposed spaced teeth integral with said downwardly and inwardly disposed portion, the teeth 20 of a bead being disposed substantially parallel to a respective flange, the teeth of said beads normally intermeshing and disposed in a unitary arcuate plane, and means for normally holding said jaws closed and the teeth of said beads 25 intermeshed.

12. A hair wave presser, comprising, in combination, juxtaposed hingedly connected arcuate complementary clamping jaws each having a reinforced manipulatable portion and each including a free depending longitudinally disposed hollow terminal bead comprising inwardly extending spaced and free teeth, the teeth of said beads being normally in mesh and disposed in the same plane, and means for normally holding said jaws closed and the teeth of said beads in mesh, the reinforced manipulatable portions of said jaws constituting means for opening said jaws to space said beads apart and dispose the teeth thereof out of mesh.
